UNITED STATES PATENT OFFICE.

CHARLES M. WELCH, OF OGDEN, ARKANSAS.

ELECTRICAL TRANSFORMER-CONTAINING CASE.

Application filed October 24, 1921. Serial No. 510,169.

The object of my invention is as follows:

(A) To secure the abolishment of using cast iron cases in distribution service transformers with an all sheet metal containing case, convenient to make up in various forms and dimensions to suit conventional core and coil designs, with simple parts easily constructed in any first class sheet metal shop without the use of expensive forming dies or much other special machinery.

(B) To secure a substantial all sheet metal containing case as above, of various forms and dimensions, which may be readily adapted as a replacement case for any make, style or type, fluid insulated core and coil unit transformer now in service in obsolete cases.

(C) To secure a case construction readily adaptable to my improvement in transformers, described and claimed in my application Number 495,522 filed Aug. 26, 1921, whereby the transformer is protected against water in the oil through a simple inexpensive means.

(D) To secure an automatic safety valve arrangement on all distribution transformers using these cases, whereby excess pressure inside the case is relieved, with the arrangement operating to extinguish combustion of the oil in case of fire arising from any temporary electrical disturbances within the case.

(E) To secure convenient outlets to the supply and service connections.

I attain the object by the arrangement illustrated in the accompanying drawings in which:

Fig. 1, is a vertical section, showing detail assembly of the essential parts.

Fig. 2, is a top view, with the cover removed, showing the arrangement of the terminals and the supporting element adjacent the top.

Fig. 3, is a back view, showing the hangers and rear terminals and the general outline with the cover on the casing.

Fig. 4, is a horizontal section on X—Y taken in Fig. 3, and illustrates the arrangement of the parts adjacent the bottom of the case, and also shows a novel form of core and coil used in the assembly. The type of core and coil shown is otherwise shown and claimed in my applications for, electrical transformer, Number 510170 filed Oct. 24, 1921, and, electrical transformer core or magnetic circuit, Number 510168 filed Oct. 24, 1921.

Fig. 5, is a horizontal section on X—Y illustrating a conventional multiple magnetic circuit transformer in the case.

Fig. 6, is a horizontal section on X—Y illustrating a conventional core type magnetic circuit transformer in the case.

Fig. 7, is a horizontal section on X—Y illustrating a conventional shell type transformer in the case.

These drawings illustrate, in connection with the description and the claims, the novel features of the sheet metal casing, the banding strip around the top of the casing, the terminal pockets formed by the banding strip, the all sheet metal cover, cover holding arrangement, horizontal holding bolts, transformer supporting means, centering means, movable element comprising safety valve arrangement, limitation by the cover holding bolts of the up and down movement of the movable element, supporting and suspension members cooperating with the cover in the use of the same holding bolts for suspending the transformer from the cover and also holding the cover on the casing, a transformer suspended from the cover having leads secured to the case, and other details contributing to the success of the combination claimed. Similar letters refer to similar parts throughout the several views in which:

The case body A is formed of sheet metal with welded seams for holding the fluid. The banding strip E is also formed of sheet metal and is placed around the top of the case body A in such fashion that offset portions forms the terminal pocket walls which terminal pockets are shown F, G, H. The cover C is made of sheet metal formed to fit the contours of the banding strip with an extension lip C¹ forming a convenient overhang with free clearance between the lip C¹ and the banding strip E.

The supporting ring B adjacent the top of the case, suspends the transformer in the fluid. This ring B is attached to one end of the suspension pieces M. The other end of the suspension pieces M are fastened to the intermediate suspension ring B². The intermediate suspension ring B² is fastened to the top of the transformer angle iron core clamps J. The bottom of the angle iron core clamps J are fastened to a centering ring N. The core clamps J hold the transformer in position through the medium of the compression bolts L which clamp the

core on parallel sides in conventional way. The core clamps shown are U-shaped pieces of angle iron extending across the edges of the top and bottom of sides of the core K, but the invention would be operative with parallel core clamps held by compression bolts L on the top and bottom of the core with the said parallel top and bottom core clamps held together by other vertical compression bolts extended beyond the face of the core and coil unit in conventional way. The pieces W¹ shown in section are wood blocks used in connection with clamping the core shown in proper alignment. The foregoing described ring B, pieces M, ring B², clamps J, bolts L, ring N, and blocks W¹, constitute a supporting member for the elements consisting of the transformer unit T having a core K and which said supporting member comprising the foregoing with attached parts and the element units will be hereinafter further described and referred to as the movable member.

Between the portions of the top edges of the banding strip and the case body A and the horizontal flange of the cover C resting upon them is placed a felt gasket D filled with insulating gum. Conveniently located around the overhanging lip C¹ of the cover C the horizontal holding bolts I form a detachable means of fastening the cover on the casing. The reference character I in Fig. 2, indicates the bolt spacing of the bolts I shown in Fig. 1. The holding bolts I are arranged in horizontal fashion and pass with free clearance through holes drilled in the cover extension lip C¹ thence through slotted holes in the banding strip and the case body wall and they are detachably fastened to the supporting ring B. The ring B and the cover C with attached parts are held relatively fixed by the bolts I which can move up or down in the slots in the casing by application of force to any attached part. The up and down movement of the transformer, suspended as described from the cover, is regulated or limited by the bolts I acting as stop pins bearing against the cover and the case, whereby the extremities of the slotted holes are varied relative to the location of the said bolts. My invention is not limited to only the same set of bolts for holding the cover and suspending the transformer as it is obvious certain advantages of my invention may be secured by suspending the transformer directly from the cover in conventional way and fastening the cover by other means consisting of bolts secured to the casing and forming stop or limiting pins against an up and down movement of the cover and suspended transformer, although this may be at the sacrifice of bringing the leads through the case, and by the words or term "detachable holding bolts acting as stop pins bearing against

the cover and the case," etc., in my claims, all such constructions are obviously included. The various parts comprising the movable member are proportioned to secure a sliding fit as it is necessary to slide the principal parts into the casing in assembly and for the automatic up and down movement of the member, and the supporting ring B and the centering ring N are especially fit to slide along vertical parallel sides of the case wall.

Openings O are cut in the case walls adjacent the terminal pockets through which openings the terminals P are carried to the supply and service lines through insulator bushings Q or conduit pipe fitting Q¹ secured in the pockets of the case. Low voltage transformer terminals are frequently of a plural number and I insulate them separately and as a unit in adequate strength to pass through the conduit fitting Q¹ when I prefer to use the conduit pipe connection.

Hanger lugs R are spot welded to the case body with the top lug also bolted to the banding strip. These hanger lugs are bolted to the hanger hooks S.

The casing has adjacent the bottom a valve or pipe plug Y for draining watery fluid from the isolating chamber or compartment which is formed by placing a funnel shaped baffle V having an opening W in the lower part of the casing in such fashion that, any water in the oil settling by gravity to the funnel shaped baffle V will drain through the opening W into the compartment X where it is prevented from circulating into the main body of insulating fluid around the transformer.

Insulating fluid may be placed in the casing by removing a pipe plug Z in the cover C, and a valve or pipe plug forming a fluid level vent 8 indicates by overflow when a sufficient amount of fluid is in the casing. The normal fluid level is indicated by the words "fluid level" in the drawings. This novel construction renders it possible to install the transformer without removing the cover for any reason. Thus I prevent the entrance of moisture by removal of the cover in damp weather. My construction throughout supersedes and renders the removable cover without utility. In practice the cover may be secured by the bolts I being placed on under seal thereby insuring a definite guarantee period for the maker.

A suitable name plate #9 of stamped material for approved identification characteristics is secured to the banding strip. The lifting ring U is welded in the cover near the center point of gravity which serves to hold the transformer in a vertical position when being raised to the pole cross arms.

Figures 5, 6, 7, illustrate how readily my containing cases may be used to contain various type conventional transformers. In this

connection, the core clamping pieces are cut longer or shorter or are varied in number and shape to accommodate the type transformer used. But in each case they are attached to or form a part of my frame for suspending the transformer in the fluid from the cover, which cover cooperates with the said frame, whereby any conventional core clamping arrangement may be employed with the invention. In the embodiment of the invention with conventional core clamps it is obvious changes may be desirable and necessary in the form and extent and number of the supporting and suspension members herein described, and when such modified construction comes within the scope of my invention as set forth in my claims attached to and forming a part of this specification I do not restrict myself, hereunder, to the exact construction shown in the drawings.

Many transformers of obsolete case design, now in service, require new cases by reason of leaking oil, dry type, broken parts, unsymmetrical case design, small dangerous terminal pockets and insulators and crowding in the case with high temperatures, and moreover, the need of a standardized case construction embodying more safety appliances on small transformers, both from service and manufacturing standpoint, indicates my improvement is useful in the art.

I have shown a polygonal cross section case form in the drawings which I have found in the octagon and hexagon shapes secures spacious terminal pockets with the banding strip adjacent sides of the case and provides a general symmetrical arrangement. But it can readily be seen my invention may be employed in the circular form of case or in irregular figures, and while the described and illustrated construction is the best means known to me at this time for carrying the invention into effect, I do not wish to be restricted in my claims, hereunder, in the choice of material construction except as comes within the scope of my said claims.

In the present invention an automatic safety valve arrangement is secured in the casing in a novel way. A gasket rests between the horizontal flange of the cover and the top of the casing. The supporting means B carries the transformer elements herein described comprising the movable member. The holding bolts I detachably fastened to the supporting means and connected through slotted holes in the casing to the lip of the cover thereby join the valve parts which operate in the following way. The movable member and the cover are held relatively fixed by the bolts I which can move up or down in the slots in the casing and move within the limits of the extremities of the slotted holes relative to the location of the bolts, whereby the weight of the

suspended transformer pulls down in the case until the cover rests tightly on the gasket union between the case and cover. The cover can move from its tight fitting position by force of increase of pressure within the casing occurring on excessive expansion of the fluid under high heat or internal pressure from disruptive electrical discharges within the casing. Thus providing an automatic safety valve arrangement, whereby the transformer and casing provides the valve parts and the weight of the suspended transformer secures an effective valve tension. Difference in weight in transformers is offset by difference in surface area of the covers for different ratings so that the designs can be arranged to provide approximately a similar relation between the weight and the area and insure a dependable action of the valve arrangement. A large factor of safety exists between the pressure sufficient to raise the cover and a pressure great enough to burst the case, therefore I overcome with this arrangement one of the objections to sheet metal cases in practice that internal pressure may burst the case or spring the joints sufficiently to cause them to leak oil. On occurrence of fire about the surface of the oil the drawing down of the cover after the pressure is relieved naturally cuts off the supply of oxygen to the fire and stops the combustion.

What I claim is:

1. In combination, a containing case having an opening formed at its upper end, a cover for closing said opening, a transformer within the containing case comprising a core clamped together, a supporting member for the transformer in the upper part of the casing, a means for securing the said core clamping means to the said supporting member forming a suspension frame for securing the said transformer in the said case, a detachable holding means extending through portions of the cover and the case and engaging the said frame cooperating with the said cover for suspending the transformer therefrom and securing the said cover on the said case, and terminal conductors for the transformer passing through the case.

2. The combination with a fluid insulated electrical transformer of a casing with a cover, a gasket between the casing and the cover, enlarged holes in the walls of the casing, a means by which the transformer is supported inside the casing, and a series of bolts engaging portions of the cover which said bolts pass through the said enlarged holes in the said walls of the casing and with the said bolts detachably fastened to the said means by which the transformer is supported inside the casing.

3. In combination, a containing case having an opening formed at its upper end, a cover for closing said opening, a transformer

- within the containing case comprising a core clamped together, a means comprising an upper frame for joining the said core clamping means to portions of the cover whereby the said transformer is suspended from the said cover, and a cover holding means comprising a series of bolts cooperating with the said cover and the said frame and passing through enlarged holes in the said case whereby a limited up and down movement between the cover and the case is provided for.
4. In combination, a containing case polygonal in cross section, having an opening formed at one end, a polygonal cover for closing said opening and having a depending flange forming terminal pockets with sides of the containing case, a transformer within the containing case comprising a core clamped together, a supporting member for the transformer in the upper part of the casing, a means for securing the said core clamping means to the supporting member for securing the said transformer in the said case, a detachable holding means extending through the depending flange and the casing and engaging the said supporting member, and terminal conductors for the transformer passing through the said formed pockets adjacent sides of the case.
5. The combination with a fluid insulated self cooled electrical transformer, a casing therefor, a cover for the casing, a gasket between the cover and the casing, a cover extension forming a lip down over the casing, a series of bolts around the said lip of the cover and detachably fastened through the case walls, a supporting means inside the casing from which the transformer is suspended in the fluid with the said means detachably fastened in sliding fit relation to the said casing and in fixed relation fit to the said cover, a centering means in the casing, a means for inlet of fluid through the cover, a means for outlet of fluid through the casing, and a fluid level vent provided at a point near the normal fluid level.
6. The combination with a fluid insulated self cooled electrical transformer, a casing therefor, a cover for the casing, a gasket between the casing and the cover, a cover extension forming a lip down over the casing, a supporting means from which the transformer is suspended in the fluid with the said means detachably fastened in sliding fit relation to the casing and in fixed relation fit to the cover, a series of bolts around the said lip of the cover and detachably fastened through the case walls to the said supporting means inside the casing, a plurality of transformer terminal leads through the casing, a centering means in the casing, a means for inlet of fluid through the cover, a means for outlet of fluid through the casing, a fluid level vent provided at a point near the nor-
- mal fluid level, and a conduit terminal entrance comprising a pipe secured to the casing with insulated portions protecting the terminals.
7. The combination with a fluid insulated self cooled electrical transformer, of a casing with a cover, a gasket between the casing and the cover, a cover extension forming a lip down over the casing, a supporting means from which the transformer is suspended in the fluid with the said means detachably fastened in sliding fit relation to the casing and in fixed relation fit to the cover, a series of bolts around the said lip of the cover and detachably fastened through the case walls to the said supporting means inside the casing, a plurality of transformer leads through the casing, a centering means in the casing, a frame work engaging portions of the transformer and secured to the supporting means, a means for inlet of fluid through the cover, a means for outlet of fluid through the casing, a fluid level vent provided at a point near the normal fluid level, and a conduit terminal entrance comprising a pipe secured to the casing with insulated portions protecting the terminals.
8. In a transformer containing case, a case body comprising polygonal sides, a banding strip adjacent the top of the said case body, a plurality of terminal pockets formed between portions of the banding strip and sides of the said case body, and a cover for the containing case the said cover having an overhanging lip formed in outline to follow the plane of the casing sides without pockets whereby the edges of the cover show in outline substantially straight lines meeting in a plurality of angle formation around the casing.
9. A safety valve for transformers comprising in combination, a case holding insulating fluid, a valve head formed by the cover for the case, a valve tension secured by the weight of a transformer suspended from the said cover in the said fluid, and a valve seat at the union of a gasket between the said case and the said cover.
10. A pressure operated safety valve for transformers comprising in combination, a case holding insulating fluid, a valve head formed by the cover for the case, a valve stem provided in a transformer suspended in the said fluid in the said case from the said cover and having portions adapted to telescope with portions of the said case, a valve tension provided by the weight of the said suspended transformer, a valve seat formed at the union of a gasket between the said cover and the said case, and with the valve opening limited by a detachable holding means for securing the said cover on the said case the said means engaging the said cover and the said case being adapted to pro-

vide an up and down movement of the said cover on the said case.

11. In combination, a containing case polygonal in cross section having an opening formed at one end, a polygonal cover for closing said opening and having a depending flange forming terminal pockets with sides of the containing case, a transformer within the containing case comprising a core 10 clamped together, and terminal conductors for the transformer passing through the said formed pockets adjacent sides of the case.

12. In a transformer containing case, a case body comprising polygonal sides, a banding strip adjacent the top of the said case body, a plurality of terminal pockets formed between portions of the said banding strip and sides of the said case body, and

a cover for the containing case the said cover 20 having an overhanging lip extending down on the said pockets and the said sides without pockets.

13. In combination, a containing case having an opening formed at its upper end, a cover for closing said opening, a transformer within the containing case comprising a core clamped together and suspended from the cover, portions of the said case and the said cover having surfaces adapted for 30 a movement secured up or down of the said cover with suspended transformer, and detachable holding bolts for the cover acting as stop pins bearing against the said case and the said cover whereby the said movement is limited.

In testimony I affix my signature.

CHARLES M. WELCH.
